(57) **CLAIM**

The ornamental design for a pet floatation device, as shown and described.

DESCRIPTION

FIG. 1 is a perspective view of a pet floatation device showing my new design;

FIG. 2 is a top view thereof; and,

FIG. 3 is a bottom view thereof.

The broken line showing in FIGS. 1 and 2 indicates sewn stitching.

1 Claim, 3 Drawing Sheets

FIG. 2
